CLAIM

The ornamental design for display screen or portion thereof with graphical user interface for viewing x-ray images and calculating vertebral heart score, as shown and described.

DESCRIPTION

FIG. 1 is a front view of a display screen or portion thereof with graphical user interface for viewing x-ray images and calculating vertebral heart score.

FIG. 2 is a front view of a second embodiment thereof.

FIG. 3 is a front view of a third embodiment thereof; and, FIG. 4 is a front view of a fourth embodiment thereof.

The broken lines showing the display screen or portion thereof form no part of the claimed design. The remaining broken lines showing portions of the graphical user interface form no part of the claimed design.

1 Claim, 4 Drawing Sheets
